UNITED STATES PATENT OFFICE

RALPH K. MERRILL, OF GRAND RAPIDS, MICHIGAN, ASSIGNOR TO AMERICAN SEATING COMPANY, OF GRAND RAPIDS, MICHIGAN, A CORPORATION OF NEW JERSEY

DESIGN FOR A SCHOOL DESK

Application filed March 19, 1931. Serial No. 39,160. Term of patent 7 years.

To all whom it may concern:

Be it known that I, RALPH K. MERRILL, a citizen of the United States, residing at No. 1445 Seminole Road, S. E., Grand Rapids, in the county of Kent and State of Michigan, have invented a new, original, and ornamental Design for a School Desk, of which the following is a specification, reference being had to the accompanying drawing, forming a part thereof, in which the figure is a perspective view of the school desk, showing my new design.

I claim:

The ornamental design for a school desk, substantially as shown.

RALPH K. MERRILL.
